ATTORNEYS

UNITED STATES PATENT OFFICE.

ALBERT DOW COX, OF WINTERVILLE, NORTH CAROLINA.

ELECTRIC LAMP.

1,215,118.

Specification of Letters Patent.

Patented Feb. 6, 1917.

Application filed December 22, 1915. Serial No. 68,195.

To all whom it may concern:

Be it known that I, ALBERT D. COX, a citizen of the United States, and a resident of Winterville, in the county of Pitt and State of North Carolina, have invented a certain new and useful Improvement in Electric Lamps, of which the following is a specification.

My invention relates to improvements in 10 incandescent electric lamps, and it consists in the combinations, constructions, and arrangements herein described and claimed.

An object of my invention is to provide a lamp having two separate resistance or light 15 giving circuits, one of these circuits being arranged to be brought into operation prior to the other, so that in a case of the burning out of the filament of the first circuit, the second circuit may be brought into use, 20 thereby increasing the life of the lamp.

A further object of my invention is to provide a device of the type described in which the switching of the current through the second circuit is accomplished by means 25 of a partial turn of the lamp, thus doing away with any complicated switching mechanism, and also obviating the necessity of removing the lamp from the socket.

A further object of my invention is to provide a lamp having two lighting circuits one of which or both of which may be brought into use, thus giving a light of a certain candle power or one double that candle power.

35 Other objects and advantages will appear in the following specification, and the novel features of the invention will be particularly pointed out in the appended claim.

My invention is illustrated in the accompanying drawing forming part of this application, in which:

Figure 1 is a sectional view through the lamp.

Fig. 2 is a perspective view showing the filament support, and

Fig. 3 is a sectional view of a portion of the device showing the spring contact member in a shifted position.

50 Fig. 4 is a diagrammatic view showing the circuit connection.

In carrying out my invention I provide a central filament support 1 of any suitable shape, but preferably of the shape shown in the drawing. This filament support is made 55 of suitable insulating material, such as glass and bears at one end a series of outwardly

extending arms 2 which support a filament 3. One end of this filament is connected by a conductor 4 with the exterior conducting portion of a screw plug 5, the support 1 60 being preferably embedded in the plug by means of a suitable filling 6 such as plaster of Paris or the like. The opposite end of the filament 3 is connected by a conductor 7 with a terminal or contact 8 disposed at the 65 end of the support. This contact 8, it will be observed, is in the form of a spring having a lateral bow or bend at its central portion.

The support 1 is provided with a second 70 set of laterally extending arms 9, these arms supporting a filament 10, one end of which is connected by the conductor 11 with the conducting external portion of the plug 5, the other end of the filament being connected 75 by a conductor 12 with a contact button 13 disposed in registration with the end of the spring 8. The central portion 8^x of the spring 8 is arranged to engage the central terminal or contact 14 of the socket 15. 80

From the foregoing description of the various parts of the device, the operation thereof may be readily understood. The bulb 16 may be of the usual shape and one end is firmly secured to the screw plug 5. 85 The latter is designed to fit any standard socket 15 so that when it is screwed into the socket, the lamp will be retained firmly in position. The bowed portion 8^x of the spring contact 8 is not only at the center 90 of the spring but at the center of the screw plug, that is to say, on the axial line of the lamp, so that when the lamp is screwed in, the portion 8^x comes into engagement with the contact 14. This causes a current to 95 pass through contact 8, conductor 7, filament 3, and by conductor 4 back to the screw plug 5, thereby causing the lighting of the lamp by means of the filament 3.

This condition is shown in Fig. 1, and it 100 will be obvious that the filament 10 may be brought into circuit by screwing the plug 5 in a little farther, so that the contact 8 will engage the contact 13, whereupon part of the current will flow through the contacts 8 and 13, conductor 12, filament 10, conductor 11, to the conducting portion of the plug 5. With both filaments in circuit, the lamp of course will give double candle power. It is only necessary to turn 110 the plug a portion of a revolution in order to bring the contacts 8 and 13 together.

This may be done by anyone and thus obviate the necessity of throwing a switch.

One of the advantages of this device is that the life of the lamp is virtually doubled, since one filament may give normal candle power, and may be burned until it is burned out, whereupon a partial turn of the lamp will bring the other filament into play. The expense of manufacturing the lamp consists largely of the bulb, plug, filament support, etc., but it is obvious that where the life of the lamp will be doubled the expense of making the lamp will not be doubled, but will be only slightly in excess of that required for one filament.

Another advantage of the lamp is that in cases where extra light is needed it may be had at any time by a partial turn of the lamp.

In Fig. 4 I have shown a modified form in which the end filament carried by the arm 2' is connected with a button 13' while the other filament carried by the arm 9' is connected with the spring 8'. The latter filament therefore lights up first and the filament carried by the arm 2' lights up after the lamp has been screwed up farther. I may use either arrangement without departing from the spirit and scope of the invention.

I am aware that lamps having separate

filaments are not new, and I do not claim such broadly.

I claim:—

An incandescent electric lamp comprising an insulating filament support, two sets of laterally extending arms carried by said support, a filament carried by each of said sets of arms, a screw plug secured to one end of said insulating support, said screw plug having a pair of contact surfaces and an inner filling between said contacting surfaces and said insulating support, a spring contact having a bowed contact portion, said spring contact being secured to the end of the insulating support adjacent to the screw plug and being connected to one of said filaments, the other terminal of the filament being connected with the conducting portion of the screw plug, a contact button carried at the same end of said insulating support and arranged to be engaged by said spring contact, said contact button being connected with the other of said filaments, the opposite terminal of said last named filament being in electrical connection with the contacting surface of the screw plug, and a bulb inclosing said filaments.

ALBERT DOW COX.
